UNITED STATES PATENT OFFICE

ADIEL Y. DODGE, OF SOUTH BEND, INDIANA, ASSIGNOR TO BENDIX RESEARCH CORPORATION, OF SOUTH BEND, INDIANA, A CORPORATION OF INDIANA

PROPELLER

Application filed June 16, 1930. Serial No. 461,369.

This invention relates to propellers and more particularly to propellers for aircraft.

An object of the invention is to provide a propeller in which the resistance or force imposed upon the propeller tends to decrease the pitch of the propeller blades.

Another object of the invention is to provide a propeller in which the resistance or force imposed on the propeller proportionally decreases the pitch of the blades of the propeller.

Another object of the invention is to provide a propeller in which each blade is free to find its own pitch within certain limits.

Another object of the invention is to provide a propeller in which each blade is free to find its own pitch within a limited range and the change in the pitch of one blade reacts against the opposite blade so that the blades are differentiated or compensated.

A further object of the invention is to provide a propeller having means for normally maintaining the blades thereof at the maximum pitch angle and permitting a variable pitch of the blades proportioned to the resistance or force encountered.

A further object of the invention is to provide a propeller in which the centrifugal force about the axis of rotation is balanced between the blades, so that only a small load may be imposed on the bearings on which the blades revolve on their longitudinal axes.

A further object of the invention is to provide a propeller in which the center of pressure of each blade is located toward the trailing edge or away from the axis of rotation of the propeller, so that the pitch of the blades will vary proportionally to variations in the resistance or force encountered.

Other objects and the structural details will appear from the subjoined description taken in connection with the accompanying drawings, in which:

Figure 1 is a front elevation of a propeller embodying the invention;

Figure 2 is a vertical sectional view through the hub of the propeller;

Figure 3 is a sectional view substantially on line 3-3, Figure 2;

Figure 4 is a perspective view of one of the anchor members;

Figure 5 is a sectional view of a modification of the propeller;

Figure 6 is a sectional view substantially on line 6-6, Figure 5; and

Figure 7 is a sectional view of another modification.

Referring to the drawings for more specific details of the invention, 10 represents a crank shaft of an internal combustion engine. A propeller hub 11 is fixedly secured on the shaft. As shown, the hub is formed in two parts, secured together as by clamps 12. The parts when assembled provide a cylindrical body 13 having a lateral sleeve 14 adapted to fit on the shaft 10 and diametrically disposed sleeves 15 and 16 which receive the shanks 17 and 18 of the respective propeller blades 19 and 20. The shanks are positioned for rotation in the sleeves 15 and 16.

As shown, each of the shanks comprise a hollow cylindrical body provided with an external shoulder 21 and a portion adjacent to its end having an enlarged inner diameter 22 terminating in splines 23.

A sleeve 24 having a circumferential flange 25 is threaded in the end of the shank in the enlarged diametral portion with a ball bearing 26 fitted on the sleeve and clamped in position between the extreme end of the shank and the flange. Positioned on the shank and bearing against the shoulders 21 is a ball bearing 27. This bearing is secured against displacement by a retaining nut 28 threaded in the end of the sleeve in which the shank of the propeller is positioned and the clamp 12 is threaded on the sleeve over the retaining nut.

The bearings 26 and 27 suitably support the propellers for rotation upon their longitudinal axes within a range limited by a suitable stop 30 on the clamp and a pin 31 on the shank. Other means for limiting the movement of the propellers on their longitudinal axes may be provided.

Positioned in each of the sleeves 15 and 16 is an anchor member 32. As shown, the anchor member comprises a sleeve 33 having a flange 34 splined as indicated at 35 and a conical portion 36 terminating in a rectangular portion 37 slotted as indicated at 38 and provided with oppositely disposed apertures 39, the object of which will hereinafter appear.

The anchor members are fitted in the sleeves 15 and 16 in oppositely disposed relation with respect to each other. As shown, the splines 35 on the anchors engage the splines in the sleeves and the anchors are

retained in position by the sleeve 24 threaded in the end of the shank and diametral bolts 39 passing through the shanks, the sleeves 24 and the anchor members.

- 5 The anchor members are secured together by a laminated leaf spring 40, the respective ends of which are secured in the rectangular portions of the anchors as by bolts 41. This leaf spring serves to retain the blades 10 of the propellers at the maximum pitch angle and the centrifugal force about the axis of rotation of the propellers is balanced through the spring, thus leaving but a small load on the bearings 26 and 27. It will be 15 observed that each blade is free to find its own pitch within a limited range and that movement of one of the blades on its longitudinal axis reacts on the opposite blade and hence the blades are differentiated or compensated.

A modification of the invention is illustrated in Figures 5 and 6. In this embodiment, two springs 42 connect the anchor members 32. These springs are arranged in 25 spaced relation, so that the driving shaft may pass between them. This type is preferred in instances where the shaft 10 extends through the body of the propeller and in Figure 7, I have shown a further modification. In this embodiment, the spring 40 passes through a slot 43 in the propeller 30 shaft.

It may be found desirable to provide an 35 adjustable friction means for the blades and to that end friction blocks 44 are positioned in the sleeves 15 and 16 in engagement with the shanks 17 and 18 and these blocks are made adjustable through set screws 45 mounted in the wall of the sleeves, or other 40 suitable adjustment means may be employed.

It will be observed that the center of pressure on each blade is located towards the trailing edge or away from the longitudinal axis of the blade so that air pressure acts 45 against the spring and hence the greater the air pressure the smaller the pitch of the blade.

It will also be observed that centrifugal 50 force about the rotating axis of the propeller acts through the spring, so that at high speed, the pitch tends to decrease. It is apparent that in cases where it is desirable, the blades may be counterweighted to reduce the action of the centrifugal force about the 55 longitudinal axis of the blade.

While preferred embodiments of the invention have been described, it is to be understood that these are given merely as examples of the underlying principles of the 60 invention and since these may be incorpo-

rated in other specific mechanical structures, I do not intend to be limited to those shown, except as such limitations are clearly imposed by the appended claims.

Having thus described the various features of the invention, what I claim as new and desire to secure by Letters Patent is:

1. A propeller comprising a hub having diametral sleeves, blades having shanks positioned for rotation in the sleeves, cone shaped anchors positioned in the shanks in oppositely disposed relation with respect to each other, means securing the anchors to the shanks and a laminated leaf spring connecting the anchors. 80

2. A propeller comprising a hub, a plurality of blades rotatably carried by said hub, a rotatable shaft for driving the hub, resilient members interconnecting the inner ends of said blades and normally maintaining said blades at a maximum pitch angle, said blades being supported forwardly of the center of pressure thereof to effect a reduction in pitch of the blades in accordance with air resistance thereon during 90 rotation.

3. A propeller comprising a hub, blades positioned for rotation thereon, a rotatable shaft, means for drivably connecting said hub and shaft, single means interconnecting the blades to normally maintain them at a maximum pitch angle, and means for decreasing the pitch of said blades in operation, said last-named means being operable 95 in accordance with air resistance encountered by the blades. 100

4. A propeller comprising a hub, a plurality of blades rotatably carried by said hub, a rotatable shaft, means for drivably connecting the hub and shaft, a laminated leaf spring interconnecting the inner ends of said blades interiorly of the hub for normally maintaining said blades at a maximum pitch angle, and means for supporting 105 said blades to effect a reduction in the pitch thereof in response to air resistance during operation.

5. A propeller comprising a hub, a plurality of propeller blades rotatably supported therein, and torsionally resistant means interconnecting the root ends of said blades and normally maintaining the latter in such position that the pitch thereof is a predetermined maximum, said blades being 110 automatically rotatable about their longitudinal axes in accordance with air resistance encountered thereby during operation of the propeller for decreasing the pitch thereof. 120
